FOREIGN PATENT DOCUMENTS

EM 008168900-0001 * 9/2020

Primary Examiner — Paula Allen Greene(74) *Attorney, Agent, or Firm* — Law Offices of Steven W. Weinrieb(57) **CLAIM**

The ornamental design for a headset, as shown and described.

DESCRIPTION

FIG. 1 is a front, right side, top perspective view of a HEADSET showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof; and,

FIG. 7 is a bottom plan view thereof.

The broken depict portions of the headset that form no part of the claimed design.

1 Claim, 7 Drawing Sheets(56)
